UNITED STATES PATENT OFFICE.

ARTHUR R. SMITH, OF SCHENECTADY, NEW YORK, ASSIGNOR TO GENERAL ELECTRIC COMPANY, A CORPORATION OF NEW YORK.

INTERLOCKING PLUG-SWITCH.

No. 839,480.

Specification of Letters Patent.

Patented Dec. 25, 1906.

Application filed September 21, 1904. Serial No. 225,311.

To all whom it may concern:

Be it known that I, ARTHUR R. SMITH, a citizen of the United States, residing at Schenectady, county of Schenectady, State of New York, have invented certain new and useful Improvements in Interlocking Plug-Switches, of which the following is a specification.

This invention relates to switches for electric circuits, and especially to those in which the circuit is closed by inserting a plug of conducting material into a socket containing terminals to be connected. Such switches are used in central stations to connect feeder bus-bars with any phase of a two-phase or three-phase circuit, especially when it is desired to change the circuits fed from any given machine. It is evident that when a system of single plug-switches provides for connecting any bus-bar with any circuit it is possible to insert two plugs in such a manner as to connect the same circuit with both terminals of the same generator, thus short-circuiting the main circuit. My invention aims to prevent the possibility of such an accident. I accomplish this by arranging the sockets for the plugs in pairs, the two sockets in each pair being so related to each other that when a plug is in place in one of them it blocks the entrance to the other socket, so that a second plug cannot be inserted therein.

The invention is also applicable to any situation where a given conductor is to be connected with either one of two other conductors, but not with both at once.

In the accompanying drawings, Figure 1 is a side elevation. Fig. 2 is a top plan view. Fig. 3 is an elevation of the terminal plate. Fig. 4 is a front elevation of a portion of the supporting-panel, showing the recess for the escutcheon; and Fig. 5 is a view of the split thimble.

The sockets are supported on the back of a panel 1, of insulating material, in which are drilled two holes 2 2'. A recess 3 is preferably made in the front of the panel, including both the holes, and adapted to receive a flanged escutcheon 4, containing two holes registering with the holes 2 2'. A metal tube 5 extends through each of said holes, being preferably provided with a flanged front end, which is clamped against the face of the escutcheon by a nut 6 meshing with external screw-threads on the rear portion of

the tube behind the panel. Between the nuts and the panel is inserted a metal plate 7, having a terminal 8 secured thereto. The plate has forked ends to straddle the tubes and lie under the nuts.

The end of the tube 5 at the back of the panel is attached by a union 9 to a tube 10, of insulation, in alinement with the tube 5. At its rear end the tube 10 passes through a bar 11, of insulation, suitably supported on brackets 12, fastened to the panel. A sleeve 13 is secured to the tube 10 and has an outwardly-projecting flange which rests against a shoulder surrounding an opening in a metal plate 14, secured to the bar 11. A split metal thimble 15 is arranged in line with the tube 10, and its flanged end is clamped against the end of the tube 10 and that of its flanged sleeve by a cap 16 screwing into a socket on the plate 14 and serving to protect the thimble. A clip 17 is attached to the plate 14.

The plug is composed of an insulating-handle 18, attached to a tube 19, of metal, adapted to slide easily into the tubes 5 10 and having a solid tip 20 to enter and make contact with the thimble 15. In order to insure good metallic contact between the plug and the tube 5, a split thimble 21 is secured in the tube 5 and hugs the tube 19 when the latter is thrust into the socket.

The operation is as follows: Inasmuch as the sockets are arranged with their mouths close together, but diverging from each other, it follows that when a plug is inserted into one of them—say the hole 2—as shown in Fig. 1, thereby closing the circuit between the terminal 8 and the clip 17 at the end of the socket in which the plug has been inserted, the handle of the plug stands across the hole 2, so that a second plug cannot be thrust into the other socket or even entered therein. The device is thus rendered "fool-proof" and all danger of accidental short-circuiting by closing both switches at once is effectually prevented.

While I have shown only two sockets, yet it is evident that the invention is applicable to a plurality of them in case it is desired to cut in any one and only one of several branch lines.

It is apparent that the invention may be embodied in various forms, and I therefore do not desire to be restricted to the specific

form shown and described, but intend to cover by the claims all changes and modifications which are within the spirit and scope of my invention.

5 What I claim as new, and desire to secure by Letters Patent of the United States, is—

10 1. A switch comprising a plurality of sockets which intersect if prolonged, and contact-plugs for said sockets extending when in operative position beyond the point of intersection of the prolongations of the sockets, whereby the insertion of one plug prevents the insertion of another plug into an adjacent socket.

15 2. A switch comprising a plurality of switch-sockets and a contact-plug formed to intersect the axes of the other switch-sockets when inserted in one of them.

20 3. A switch comprising a plurality of sockets intersecting when prolonged, and contact-plugs extending beyond the point of intersection when in operative position.

25 4. A switch comprising a suitable support, sockets mounted thereon so that said sockets when prolonged intersect near said

support, and contact-plugs extending beyond said point of intersection when in operative position.

5. The combination with a supporting-panel having adjacent holes, of a plug-switch comprising sockets mounted adjacent said holes in such position that said sockets intersect when prolonged, and contact-plugs extending beyond the point of intersection when in operative position whereby the insertion of one plug prevents the insertion of another.

10 6. The combination with a supporting-panel having two adjacent holes, of metallic tubes extending through the same, a terminal plate adjacent to said tubes, nuts on said tubes clamping said plate to the panel, and terminals insulated from but in line with said tubes.

15 In witness whereof I have hereunto set my hand this 19th day of September, 1904.

ARTHUR R. SMITH.
